(57) **CLAIM**

The ornamental design for a noise filter case, as shown and described.

DESCRIPTION

FIG. 1 is a perspective view of a noise filter case;

FIG. 2 is a front view thereof;

FIG. 3 is a rear view thereof;

FIG. 4 is a top view thereof;

FIG. 5 is a bottom view thereof;

FIG. 6 is a left-side view thereof;

FIG. 7 is a right-side view thereof; and,

FIG. 8 is an enlarged fragmentary view thereof.

The broken lines shown represent environmental subject matter and form no part of the claim. Where broken lines abut a claimed surface it is understood that those broken lines represent an unclaimed boundary between claimed and unclaimed surfaces. None of the broken lines form any part of the claimed design.
